BUTTON COMPANY, OF NEWARK, NEW JERSEY, A CORPORATION OF NEW
JERSEY.

IGNITER.

1,079,002.

Specification of Letters Patent.

Patented Nov. 18, 1913.

Application filed December 7, 1910. Serial No. 596,022.

To all whom it may concern:

Be it known that I, FREDERICK W. GOERDES, a citizen of the United States, residing in the city of Newark, county of 5 Essex, and State of New Jersey, have invented certain new and useful Improvements in Igniters, of which the following is a specification.

My invention relates broadly to igniters 10 of the friction type, and particularly to that class wherein, by contact of a block of spark-producing material or friction alloy with a harder substance, sparks are produced which may be caused to impinge upon 15 an inflammable substance or upon a wick saturated with a volatile combustible liquid, thus producing a flame.

The object of my improvement is to render the ignition of the inflammable material more certain and to increase the life 20 and efficiency of the operating parts. This I attain through the provision of means for automatically obtaining positive contact between fresh spark-producing surfaces at 25 successive operations of the device.

My invention may be embodied in means of small compass, and therefore is especially adapted for use as a pocket lighter.

In my improved device the opening of 30 the cover of the igniter automatically draws a block of spark-producing substance across the face of a toothed wheel of steel or other hard material. Fine particles are thereby cut or chipped from the block, the 35 heat produced by this action being sufficient to raise these particles to incandescence, and thus to form sparks which may be utilized in producing a flame.

A portion of my invention relates to the 40 provision of means whereby a new cutting edge is brought into contact with the spark-producing material or friction alloy at each operation of the igniter, and I proportion the device in such a way that the cutting 45 surface of the wheel does not always come in contact initially with the same portion of the abrasive block. In this manner wear on the abrasive block or friction alloy is made more uniform and the life of the cutting member is prolonged.

In the accompanying drawings which form a part of this specification, Figure 1 is a sectional view through one form of my improved device, illustrating in detail the operative mechanism; Fig. 2 is a transverse 55 sectional view on line I I of Fig. 1; Fig. 3 is a sectional view on line I I of Fig. 1.

Referring to the drawings in detail, numeral 1 designates a case, to which the cover 2 is attached by means of the hinge 3. 60 Affixed to the case is the mechanism-carrying structure 4, in which is journaled the shaft 5 carrying the toothed rotatable cutting member 6. Secured to this toothed member and concentric with it is the ratchet 65 disk 7. The teeth of the ratchet disk are engaged by the spring pawl 8. Pivoted to the pin 9 in the cover is the arm 10, carrying on its other extremity the block 11 of spark-producing material. A spring 12 is provided for causing the block 11 to bear with a firm pressure upon the toothed cutting member. The spring 13 acts to open the cover when the button 14 is depressed, disengaging the catch 15 from its socket 16 in 75 the cover. The partition 17 forms a cavity 18 in the lower portion of the case, wherein may be placed a quantity of cotton or other absorbent material 19, which may be saturated with some volatile material whose 80 fumes are highly combustible, such, for instance, as benzine, gasolene or alcohol. A tubular structure 20 passes through the partition 17, and within this tubular structure is placed a wick 21 the exposed end of 85 which, 22, is placed in such a position as to receive sparks which may be formed by the action of the block of spark-producing material in rubbing across the face of the toothed wheel. The lower end of the wick 90 extends down into the chamber 18 and the entire wick is thus kept moist by the liquid which saturates the filling placed therein. A screw 23 is provided in order to furnish access to the lower cavity of the case when 95 it is desired to replenish the supply of liquid therein.

The arm 10 I preferably form from a single piece of sheet metal stamped into the shape shown, and I provide it with the two 100

outstanding lugs or ears 24, adapted to limit the motion of the operating parts by contacting with the abutments 25 when the cover is raised.

5. The operation of my device is as follows: When the button 14 is depressed, thus releasing the catch which normally holds the cover shut, the spring 13 will cause the cover to open automatically. The pin 9 is thereby 10 displaced and the arm pivoted to this pin caused to move in an approximately horizontal direction, drawing the block of spark-producing material sharply across the face of the toothed wheel. Sparks will thereby 15 be formed, which, impinging upon the exposed portion of the wick, will cause a flame. When the cover is shut, the block of spark-producing material will slide back across the face of the toothed cutting member and 20 will cause the same to rotate through a small arc. As the teeth of the ratchet disk are opposed in direction to those of the cutting member, rotation is permitted when the cover is being closed, but the toothed 25 cutting member is held stationary when the block of spark-producing material is drawn across the face of the cutting member as the cover opens. As a result of this action, a new set of teeth is brought into 30 contact with the operative surface of the spark-producing material each time the cover is closed, and the wear is distributed among all the teeth of the cutting member. Since the cutting member is not always rotated through an arc equal to a whole number 35 of teeth when the cover is closed, the principal tooth in contact with the operative surface of the spark-producing material or friction alloy will not always be in the same 40 initial position with respect to the block, and therefore the wear is much more nearly even over the surface of the spark-producing block than it would be were a single stationary knife edge used in place of the 45 rotary cutting member.

I prefer to use as the spark-producing material or friction alloy the substance known to the trade as "cerium," but other hard materials, such as flint or emery, may 50 be used for this purpose, and I have used these terms interchangeably in a generic and not in a special sense in the subjoined claims.

While I have illustrated and described 55 only one specific embodiment of my invention, I believe it to be susceptible of broad application and I do not wish to be limited to the modification shown in detail.

Having thus described my invention, I 60 claim:

1. In an igniter, in combination, a case, a cover therefor, and spark-producing means

including a cylindrical cutting element capable of free rotation in one direction, and a block of spark-producing material 65 carried by the cover and moved thereby across said cutting element.

2. In an igniter, in combination, a case, a cover therefor, and spark producing means including a block of spark producing alloy, 70 a rotatable, cylindrical cutting element, means for reciprocating the one across the face of the other, and means for maintaining the cutting element stationary while the cover is opening. 75

3. In an igniter, in combination, a case, a cover therefor, and spark producing means including a block of spark producing material, a rotatable cutting element, and means whereby the reciprocation of the 80 block across the cutting element causes fresh portions of said element to contact with said block.

4. In an igniter, a cutting element having teeth on the periphery thereof and a ratchet portion having teeth opposed in pitch to those of the cutting portion, a block of spark producing material in contact with said cutting portion, and a pawl engaging said ratchet portion capable of vibration 90 about a fixed point, said pawl acting to hold said cutting element stationary during the opening of the cover. 85

5. In an igniter having a two-part case, spark producing means including a rotatable cutting element and a ratchet for preventing its rotation when the parts of 95 said case are separated.

6. In an igniter having a cover, an arm for carrying a block of spark producing 100 alloy, means for causing reciprocation of said arm by movement of the cover, and outstanding lugs on said arm adapted to engage a fixed part of said igniter and thereby limit the movement of the arm and the 105 cover.

7. In an igniter having a cover, a unitary arm secured to said cover and adapted to be reciprocated by movement thereof, said arm having a tubular structure formed at one 110 end to receive a block of spark producing alloy, and unitary lugs outstanding therefrom adapted to engage a fixed portion of said igniter and thereby limit the movement of the arm and cover. 115

8. In an igniter, in combination, a case, a cover therefor and spark-producing means including a cylindrical cutting element rotatable about its axis in one direction, an arm pivoted to the cover, and a block of 120 spark producing material mounted on said arm and adapted to be drawn across said cutting element by movement of the cover.

9. In an igniter, in combination, a case, a

cover therefor and spark-producing means including a rotatable cutting element, a block of spark-producing material, yieldable means for forcing the block into contact with the cutting element, and means operated by movement of the cover for drawing the block across the cutting element in a direction opposed to the direction of rotation of said element.

FREDERICK W. GOERDES.
